VALVED BOTTLE CAP

Alan H. Graham, Upper Montclair, N. J.

Application November 23, 1934, Serial No. 754,444

6 Claims. (Cl. 215—39)

This invention relates to improvements in valved bottle caps, and more particularly to a cap of the common crown seal type having valved means provided therein for releasing the contents of the bottle held under pressure, and for conserving any unused portion of the contents. This invention is an improvement upon the bottle cap described and claimed in my Patent No. 1,963,050, granted June 12, 1934.

An object of the invention is to provide means for permitting the gradual dispensing of carbonated beverages in bottles and to conserve any unused portion of the beverage without loss of pressure. A further object is to provide means for doing this in a simple economical and practical manner, by making use of the common crown seal cap in a way which will not materially increase the cost of manufacture of the bottle cap, and which will permit its use in standard capping machines.

As is well known, a bottle of carbonated beverage having the ordinary crown seal cap must be used immediately, once the cap has been removed, or the beverage quickly loses its carbonation. Merely replacing the cap still allows the carbonation of the remaining fluid to be lost. Neither is it possible with the ordinary crown sealed bottle to dispense the liquid in a thin forcible stream, known as fizzing, in any satisfactory manner without separate and relatively expensive means.

My invention consists briefly in providing the ordinary crown seal cap with a chamber beneath the cap to carry valve means adapted to release the contents of the bottle on breaking through the seal, and to maintain the bottle in sealed condition after first use. I provide a metal disk or plate between the cap and the cork packing having a chamber formed therein for carrying the valve means. In this way my invention permits the use of the ordinary crown seal cap with its cork packing for sealing the bottle and permits capping in the standard capping machines. An important advantage of this device is that the bottle remains completely sealed in its original condition until ready to be used, and there is no possibility of leakage through the valve means. When the beverage is to be consumed, the seal is broken through for the first time by piercing the inner disk through the valve aperture with a suitable sharp pick or other instrument. The beverage is then dispensed through the small hole thus provided, and to conserve any unused portion of the contents, the valve is moved to closed position, thereby sealing the cap again.

In this way the possibility of leakage through the valve is prevented until after the bottle has been opened, when the danger of such leakage is no longer a serious problem. My valve means, however, is made tight enough so that the possibility of leakage, after the bottle has been opened, is very slight.

Other objects and advantages of my invention appear in the following specification and drawings wherein—

Fig. 1 is a plan view of my improved valve bottle cap in closed position;

Fig. 2 is a vertical cross section taken on line 2—2 of Fig. 1;

Fig. 3 is a plan view of my device in open position, before piercing;

Fig. 4 is a vertical cross section on line 4—4 of Fig. 3;

Fig. 5 is a perspective view of the valve seat;

Fig. 6 is a perspective view of a modified form 20 of valve seat showing different means for moving the valve seat;

Fig. 7 is a vertical cross section on line 7—7 of Fig. 6;

Fig. 8 is a plan view of a combination tool to be used with my bottle cap;

Fig. 9 is a side elevation of the same device;

Fig. 10 is a plan view of my modified form of bottle cap in closed position; and

Fig. 11 is a vertical section on the lines 11—11 30 of Fig. 10.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose 40 of description and not of limitation, and it is not intended to limit the invention claimed herein beyond the requirements of the prior art.

In Figs. 1 to 5, the first form of my improved valved bottle cap, 10 indicates the neck of the glass bottle, having the usual annular shoulder 11, which is gripped by the crimped sides 13 of the crown seal metal cap 12. Two apertures 14 and 15 are provided in the top of said cap, the aperture 14 preferably on one side of the top and the aperture 15 preferably in the center. The aperture 14 provides an opening for the bottle while aperture 15 provides space for moving the valve by means of a handle or detachable key. A 55 metal plate 16 having a centrally depressed por-

tion 17 forming a valve chamber 19 fits in the cap 12 between the usual cork packing and the cap. An annular ring 18 of cork or other compressible material encircles depressed portion 17 of plate 16 and performs its usual function of sealing the bottle.

Within the valve chamber 19 formed by the depressed portion 17 of plate 16 is carried the valve seat or valve mechanism 20 (Fig. 5). This consists of a thin metallic disk 21 out of which is formed a handle 22, the disk 21 being backed with a relatively thick layer 23 of compressible material, such as cork, to prevent leakage of pressure around the valve seat. Teeth or prongs 24 may be pressed from disk 21 for engaging the cork disk 23, and cork disk 23 is fixedly attached to metal disk 21 preferably both by the prongs 24 and a suitable adhesive. It is to be understood that the valve seat 20 may be made entirely of a very malleable metal or other material, if desired. An aperture 25 is provided through plate 21 and cork disk 23 as to register with the aperture 14 in the metal cap 12. Handle 22 extends through hole 15 in cap 12, and provides means for moving the valve mechanism 20.

It is important, to prevent leakage after the seal has been pierced, that there be a relatively tight fit between the top of metal cap 12, the valve mechanism 20, and the bottom of depressed portion 17 in plate 16. The valve chamber 19 formed by depression 17 may be made just deep enough to contain the valve mechanism 20 as to be movable therein with a reasonably tight fit. The same purpose may be accomplished, as shown, by providing inwardly depressed or countersunk rims 14a and 15a forming an interior flange around apertures 14 and 15 in the metal cap 12. Dents in the cap 12 or raised portions on the valve disk 21, not shown, may likewise be provided for this purpose, if desired. In this way I provide the tight fit necessary to prevent leakage of gas around these apertures, and at the same time permit the valve means to be easily moved, because of the smaller frictional area. Further, to prevent leakage of gas around the apertures 14 and 15 in cap 12, after the bottle has been pierced, I have found it advantageous to fill all empty spaces around valve mechanism 20 in valve chamber 19 with paraffine or other suitable filler 26. In Fig. 5 the handle 22 is shown struck from that portion of the disk 21 which includes aperture 25. To assist in preventing leakage around aperture 25 through the handle portion, aperture 25 and handle 22 may, of course, be struck from separate parts of disk 21 if desired. The valve mechanism 20 and metal plate 16 are held in position inside cap 12 by means of the annular ring of cork 18, which is made slightly large so as to fit tightly between the sides of the depressed portion 17 in plate 16 and the sides 13 of cap 12. Any other suitable means of holding the valve parts in the cap, however, may be substituted for this means if desirable. The cork packing to seal the bottle is here shown as an annular ring 18, a hole being cut out of its center to accommodate the valve chamber 19 formed by the depressed portion 17 of the metal plate 16. It is to be understood, however, that a cork packing strip in disk form may still be used, if desired, to entirely cover metal plate 16, without departing from my invention.

To operate my valve bottle cap, handle 22 is moved to bring aperture 25 into registration with aperture 14 of cap 12. A small pick or other suitable instrument is then sharply thrust

through apertures 14 and 25 as to pierce and make a similar hole through metal plate 16, thus opening a small hole into the bottle. Inverting the bottle permits the carbonated beverage under pressure to be forced through hole 14 in the cap, until the bottle is empty or the desired amount of beverage used. To conserve any unused portion of the contents, the valve mechanism is moved to closed position by handle 22, thus sealing the bottle against further escape of the liquid or gas. In this way, the original cap is not removed but remains on the bottle at all times until no longer desired.

In Figs. 6 to 11 a second form of my improved valved bottle cap is shown, which has different means for moving the valve mechanism. Instead of the handle 22, I provide a key hole 30 in the center of the valve plate 21 in registration with aperture 15 of the cap 12. The key hole 30 may consist of any suitable indentation or non-circular hole, adapted to receive a key for turning the valve mechanism 20. In Figs. 6 and 7, I have shown the key hole 30 as a square depression formed in the plate 21. To accommodate such depression, the backing disk 23 of cork is preferably provided with a suitable hole. When the key hole 30 comprises merely a non-circular hole rather than a depressed portion in the plate 20, it is unnecessary, of course, to provide accommodation for it in the cork backing 22, as the latter is sufficiently compressible to permit insertion of the key in the key hole. The valve mechanism is then turned by a separate key having an end adapted to fit the key hole 30. In Figs. 8 and 9 I have shown such a key forming a combination bottle opener, pick, and key. This combination tool 31 comprises the bottle opening portion 32, the pick or punch 33 and the key or "wrench end" 34.

In this manner I have provided an improved valve bottle cap of the crown cap and cork seal type provided with a simple, economical and efficient valve means beneath the cap, which permits the cap to be used with a standard capping machine.

I claim:

1. A bottle stopper of the crown seal type, comprising a metallic cap having sides adapted to be fastened to the mouth of the bottle, an aperture in the top of said cap, a compressible packing in said cap for sealing said bottle, a metallic plate between said cap and packing having a centrally depressed portion forming a valve chamber, valve means in said chamber comprising a valve having an aperture movable into registration with the aperture in said cap, and operable to release the contents held within said bottle under pressure on breaking through said metallic plate when the contents are to be used, and movable out of registration therewith to maintain the bottle in sealed condition, and means for moving said valve.

2. A bottle stopper of the crown seal type, comprising a metallic cap having sides adapted to be fastened to the mouth of the bottle, an aperture in the top of said cap, a compressible packing in said cap for sealing said bottle, a metallic plate between said cap and packing having a centrally depressed portion forming a valve chamber, valve means in said chamber comprising a movable metallic disk having a backing of compressible material attached thereto and having an aperture therethrough movable into and out of registration with the aperture in said cap, and means for moving said valve means.

3. A bottle stopper of the crown seal type comprising a metallic cap having sides adapted to be fastened to the mouth of the bottle, an aperture in the top of said cap, a compressible packing in said cap for sealing said bottle, a metallic plate between said cap and packing having a centrally depressed portion forming a valve chamber, valve means in said chamber comprising a movable metallic disk having a backing of compressible material attached thereto and having an aperture therethrough movable into and out of registration with the aperture in said cap, and a handle for moving said valve means.

4. A bottle stopper of the crown seal type comprising a metallic cap having sides adapted to be fastened to the mouth of the bottle, an aperture in the top of said cap, a compressible packing in said cap for sealing said bottle, a metallic plate between said cap and packing having a centrally depressed portion forming a valve chamber, valve means in said chamber comprising a movable metallic disk having a backing of compressible material attached thereto and having an aperture therethrough movable into and out of registration with the aperture in said cap, and a key-hole in said plate for moving said valve means.

5. A bottle stopper of the crown seal type, comprising a metallic cap having sides adapted to be

fastened to the mouth of the bottle, an aperture in the top of said cap, a compressible packing in said cap for sealing said bottle, a metallic plate between said cap and packing having a centrally depressed portion forming a valve chamber, valve means in said chamber comprising a valve having an aperture movable into registration with the aperture in said cap, and operable to release the contents held within said bottle under pressure on breaking through said metallic plate when the contents are to be used, and movable out of registration therewith to maintain the bottle in sealed condition, means for providing a tight fit between said cap and valve, and means for moving said valve.

6. A bottle stopper of the crown seal type, comprising a cap having sides adapted to be securely fastened to the mouth of the bottle, an aperture in the top of said cap, a metallic plate in said cap having a centrally depressed portion forming a valve chamber, valve means in said chamber comprising a metallic disk having an attached backing of compressible material and having an aperture movable into and out of registration with the aperture in said cap, means for moving said valve means, and an annular ring of compressible packing in said cap encircling said valve chamber.

ALAN H. GRAHAM.
